UNITED STATES PATENT OFFICE.

GEORGE E. HASSMANN, OF LITCHFIELD, ILLINOIS.

DOOR-CHECK.

990,552.

Specification of Letters Patent. Patented Apr. 25, 1911.

Application filed September 20, 1910. Serial No. 582,948.

To all whom it may concern:

Be it known that I, GEORGE E. HASSMANN, a citizen of the United States, residing at Litchfield, in the county of Montgomery 5 and State of Illinois, have invented certain new and useful Improvements in Door-Checks, of which the following is a specification.

This invention relates to improvements in 10 devices for securing doors at any desired point either closed, fully opened, or partly opened, and has for its object to simplify and improve the construction and increase the efficiency and utility of devices of this 15 character.

Another object of the invention is to provide a device of this character which may be actuated by the movement of the lock or latch spindle.

20 With these and other objects in view the invention consists in certain novel features of construction and arrangement of the parts as hereinafter shown and described and then specifically pointed out in the 25 claim; and, in the drawings is illustrated the preferred embodiment of the invention.

Figure 1 is a view of a portion of a door and its frame and casing including one of the hinges with the improved device applied. 30 Fig. 2 is an enlarged front elevation of the improved device. Fig. 3 is a section on the line 3—3 of Fig. 2. Fig. 4 is a sectional detail of the knob attachment portion of the improved device.

35 Corresponding and like parts are referred to in the following description and indicated in all the views of the accompanying drawing by the same reference characters.

The improved device may be applied to 40 doors or other swinging structure of any size. For the purpose of illustration the improved device is shown applied to a conventional door, a portion of which is represented at 10 with the frame at the hinge side

45 at 11 and the frame at the latch side at 12.

The improved device resembles an ordinary hinge having leaves 13—14 and a pintle 15. The leaf 13 differs from an ordinary hinge pintle by being provided with an in-

50 wardly directed stop-web 16 and stop-lugs 17—18 at the ends of the stop-web, and the leaf 14 differs from an ordinary hinge-leaf by being provided with a guide keeper 19. The leaf 13 is connected to the hinge casing 55 or frame 11, while the leaf 14 is connected

to the door by screws in the usual manner with the pintle located in vertical alinement with the pintles of the ordinary hinges of the door.

Mounted for rotation upon the pintle 15 60 is a stop-collar 20 having a plurality of recesses 21 spaced apart in its periphery. The collar 20 is so arranged upon the pintle that one of its recesses engages constantly with the stop-rib 16, while the ends of the collar 65 extend between the stop-lugs 17—18. By this means the stop-collar is coupled to the leaf 13 both for rotative and longitudinal movement relative thereto. Slidable through the guide-keeper 19 is a bolt 22 having a slot 70 23 and held slidable within the keeper by a pin 24. The keeper 19 is formed with a recess to receive a spring 25, which is connected at one end to the pin 24 and at its other end to the bolt 22, the spring operating 75 to maintain the inner end of the bolt in yieldable engagement with one of the recesses 21 of the collar 20. By this arrangement the lug 14 may be locked to the collar 20 and through the collar to the other leaf 80 13 at any desired point within the range of the recesses. One of the recesses of the collar is so located that the bolt 22 will engage therein when the leaves 13—14 are in alinement transversely, or when the door is 85 in closed position, and then when the door is to be opened the bolt is withdrawn, and when the door has been opened to the desired extent, the bolt is released and engages in the nearest recess 21 and thus holds the 90 door firmly in the adjusted position, and is releasable only by again withdrawing the bolt. By this means it will be obvious that the door may be held at any desired point within the range of the recess 21 in the collar 95 20, and by providing a plurality of the recesses spaced a short distance apart, the "range" of the device is materially increased.

Any required means may be employed for 100 actuating the bolt 22, but will preferably be so coupled to the knob or latch spindle that when the knob is rotated to open the door the bolt will be actuated, and an approved mechanism for accomplishing this result is 105 shown in the drawings. The knob spindle is represented at 26 and the knob at 27. The screw by which the knob is connected to the spindle in the improved device is replaced by a longer screw 28, and this longer 110

screw utilized to couple a small lever 29 to the knob, the lever being thus arranged to rotate with the knob. At its outer end the lever 29 is connected by a pull-wire or cable 30 to the bolt 22 and arranged to be guided over a suitable guide-pulley 31 upon the door 10. By this simple means it will be obvious that when the door is to be opened the first movement of the knob spindle will cause the withdrawal of the bolt 22 and release the door which may then be opened to any required extent and automatically locked when the knob is released.

The improved device is simple in construction can be inexpensively manufactured and applied without making any change in the door or in the casing. The improved device may be manufactured of any required material and of any required size to adapt it to doors of different weights and sizes.

Having thus described the invention what is claimed as new is:—

A door check comprising two leaves adapted to be connected respectively to a door and its frame, one of said leaves having a stop-rib, a pintle uniting said leaves, a stop-collar having a plurality of recesses spaced apart and carried by said pintle, one of said recesses being arranged in constant engagement with said stop-rib, and a spring controlled bolt carried by the other of said leaves and adapted to engage any one of said recesses to lock said leaves against relative movement.

In testimony whereof, I affix my signature in presence of two witnesses.

GEORGE E. HASSMANN. [L. S.]
